(57) **CLAIM**

The ornamental design for an insulated container as shown and described.

DESCRIPTION

FIG. 1 is an upper perspective view of a first embodiment of an insulated container;

FIG. 2 is a lower perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1;

FIG. 8 is a bottom view of the design of FIG. 1;

FIG. 9 is an upper perspective view of a second embodiment of an insulated container;

FIG. 10 is a lower perspective view of the design of FIG. 9;

FIG. 11 is a front view of the design of FIG. 9;

FIG. 12 is a rear view of the design of FIG. 9;

FIG. 13 is a first side view of the design of FIG. 9;

FIG. 14 is a second side view of the design of FIG. 9;

FIG. 15 is a top view of the design of FIG. 9; and,

FIG. 16 is a bottom view of the design of FIG. 9.

The broken lines shown in the drawings show portions of the insulated container that form no part of the claimed design. The dot-dashed broken line shown in the drawings designates a boundary line all of within which forms no part of the claimed design. The stippling of the top surface of the insulated container designates a soft material or fabric.
